United States Patent Office

Des. 218,286
Patented Aug. 11, 1970

218,286

DECANTER

Ernest L. DuPree, New York, N.Y., assignor to Schenley
Industries, Inc., New York, N.Y., a corporation of Delaware

Filed July 14, 1969, Ser. No. 18,191

Term of patent 14 years

Int. Cl. D9—01

U.S. Cl. D9—167

FIG. 1

FIG. 2

FIG. 3

FIG. 4

FIG. 1 is a front elevational view of a decanter embodying my new design, with the rear elevational view being identical in appearance;

FIG. 2 is a side elevational view thereof, with the opposite side being identical in appearance;

FIG. 3 is a top plan view thereof; and

FIG. 4 is a bottom plan view thereof.

I claim:

The ornamental design for a decanter, as shown and described.
